UNITED STATES PATENT OFFICE.

WILLIAM P. WILCOX, OF CICERO, NEW YORK.

DESIGN FOR A CIGAR-BOX.

SPECIFICATION forming part of Design No. 19,144, dated June 4, 1889.

Application filed January 14, 1889. Serial No. 296,361. Term of patent 7 years.

To all whom it may concern:

Be it known that I, WILLIAM P. WILCOX, of Cicero, Onondaga county, State of New York, have invented and produced a new and original Design for Cigar-Boxes, of which the following is a specification, reference being had to the accompanying drawings, forming a part thereof.

Figure 1 is a side elevation. Fig. 2 is a horizontal section of Fig. 1, showing the rectangular shape of the box.

The leading feature of my design consists in a body having a rectangular top and base, provided with sides standing vertical to the base and concaved in their ends, and concave end pieces secured to the base and to the concaved ends of the side pieces.

A is the box, constructed of the rectangular bottom 3, sides 2, standing vertical to the bottom and concaved in their ends, the concave

end pieces 1, secured to the concaved ends of the sides, and the rectangular top or cover 2. The box thus constructed is rectangular top and bottom and rectangular in transverse vertical section and in horizontal section, and 25 rectangular everywhere, except in the concavity of the ends of the side pieces and the ends of the box.

What I claim is—

The design for a cigar-box herein described 3c and shown, the same comprising a rectangular box having its end pieces concaved and a bottom extending out beyond the end pieces, as shown and set forth.

In witness whereof I have hereunto set my hand this 16th day of October, 1888.

WILLIAM P. WILCOX.

In presence of—

W. E. BURLINGAME,
H. P. DENISON.
